UNITED STATES PATENT OFFICE

BURTON P. MERWIN, OF WESTON, CONNECTICUT, ASSIGNOR TO THE WESTON TOY COMPANY, INC., A CORPORATION OF CONNECTICUT

DANCING TOY

Application filed August 12, 1929. Serial No. 385,377.

This invention relates to a dancing toy and has for an object to provide an improved toy that may be used to simulate fancy or other dancing when properly operated.

5 A further object of this invention is to provide a pair of similarly jointed human figures supported above a base so that the feet may resound on said base when the toy 10 is operated.

A still further object of this invention is to provide a base of a special material which will be nonwarping and which will be stiff, yet "lively" so that the feet dangling against 15 said base will react quickly therefrom and will resound as they do so.

With the foregoing and other objects in view, this invention comprises certain combinations, constructions and arrangements 20 of parts as set forth, disclosed and claimed in the following specification taken in consideration with the accompanying drawing.

In this drawing:

Fig. 1 is a side elevation of one embodiment of this invention, the handle being partly broken away and its connection to the base shown in section.

Fig. 2 is an elevation of the back of one of the toy figures showing the leg connection in section, and

Fig. 3 is a bottom plan view of the base and handle, part of the base being peeled away to show the details.

There is shown at 10 a circular base composed of cardboard, metal, wood or the like and preferably laminated, it being here shown as comprising three laminations 11, 12 and 13, altho of course more or less may be used as found desirable. The adjacent 35 laminations or layers are usually set with their grains running in different directions to increase the strength of the board and prevent warping. The use of a laminated base provides a base that is stiff and non- 40 warping, yet is lively and will make a realistic dancing sound when struck by the dangling feet, as hereinafter described. A handle 14 is pivoted to the base 10 by any suitable means such as an eyelet 15, the 45 length of handle 14 being preferably sub-

stantially equal to or less than the diameter of the base 10 so that it may be turned to the dotted line position 14' under the base when not in use, as for storage or shipment purposes, as in this position it occupies 55 little space.

Extending upwardly from the base 10 and secured thereto by any suitable means as by a nail 16, is a pedestal 17, and pivotally affixed to the pedestal as by a nail 18 is a 60 flat flexible supporting spring 20.

Supported on each end of spring 20 is a figure preferably simulating a human figure as shown at 21 and 22. The figures may be alike but preferably differ from each other 65 in that they are designed to simulate different individuals. The two figures do not necessarily balance each other.

The figures may be cut or stamped from wood, metal, heavy cardboard or other suitable material and each of the figures 21 and 22 comprise a body portion 23 preferably cut out and designed in the general shape of a human body and head, this body 23 being 70 affixed to spring 20 by any suitable means such as a pair of nails 24 through the spring and the base of the body. Pivotally supported on each side of the body 23 at the shoulders is a pair of curved arms 25, the arms each being rotatable on the pivoting pins or nails 26. It will be understood, however, that eyelets or other pivoting means may be used instead of pins if desired. Pivotally affixed through the hips as 75 by an eyelet 27 are a pair of jointed legs 28. Each leg 28 comprises an upper or thigh portion 30, and a lower or foot portion 31 pivotally affixed thereto by a pivot pin 32 so that the feet may dangle and make contact with the base. The pivotal joints 26, 27 and 32 are all free and sufficiently loose so that the arms and legs swing freely. 80

In operation, the pivoting eyelet 15 for handle 14 is a somewhat tight joint, so that the handle may remain beneath the base 95 when in storage, and will remain at the set angle when in use. The remaining pivots, as at 18, 26, 27 and 32 are all intended to be very loose so that the parts may be rotated freely. The player will grasp the handle 100

and then will lightly tap the base against his knee or other object to agitate the figures. This will have the effect of causing the figures to sway on their flexible supporting spring and the dangling legs to strike the base and to swing back and forth, and the arms will likewise swing back and forth. Preferably, the toy will be used with music, as when dance music is being received by 10 radio or produced on a phonograph. The listener will grasp the handle and after proper practice, so agitate the device in time with the music as to cause the figures to simulate dancing both in their movements and in the sounds made by the dangling feet against the laminated base. The figures as a whole may likewise pivot or turn about the pedestal due to the fact that the connection 18 for the spring is a pivotal connection. The up and down movement of 20 the base causes the figures to also move up and down, but their movements, including the movements of the arms and legs, are modified by the flexible spring 20, and the 25 stiffness or flexibility of this spring is so designed or proportioned to the weight of the figures that very little movement is required of the base to cause the desired movements of the figures. The movements of the 30 figures are also assisted and modified by the reaction of the lively base board 10 with the feet.

Having thus set forth and disclosed this invention, what is claimed is:

35 1. A dancing toy comprising a base, a pedestal supported on said base, a flexible supporting spring pivoted on said pedestal, a pair of body figures affixed to said spring, the figures being at opposite sides of the pedestal, and jointed limbs pivoted to said figures, the feet being adapted to contact with said base.

40 2. A dancing toy comprising a supporting base, a handle pivoted thereto adapted to be 45 swung to within the outline of the base, a pedestal on said base, a flat spring pivoted on said pedestal above said base, a body figure affixed to each end of said spring, a pair of arms freely pivoted on each body, and a 50 pair of jointed legs pivotally depending from each body with the feet loosely contacting with said base.

55 3. A dancing toy comprising a supporting base, a handle extending from one side of the base, a pedestal secured to and extending upwardly from the base, a substantially horizontal spring pivoted on the pedestal above the base, a body figure secured to the spring on each side of the pedestal and spaced 60 therefrom, a pair of arms freely pivoted to each body, and a pair of jointed legs pivotally depending from each body with the feet at the top of said base.

65 4. A dancing toy comprising a base of lively material, a handle pivoted thereto,

a pedestal supported on the base, a flat spring support pivoted between its ends to the pedestal, a human figure affixed to each end of said spring support, each figure comprising an outline of a body, a pair of arms pivoted to said body, a pair of jointed legs pivotally dangling from said body with the feet adapted to loosely contact with and dance on said base when the toy is agitated. 70

5. A dancing toy comprising a laminated base, a handle at one side thereof, a pedestal affixed to said base, a supporting spring pivoted to said pedestal, a human figure affixed to each end of the spring on opposite sides of the pedestal, each figure comprising an outline of a body, a pair of arms pivoted loosely to the body and a pair of legs dangling loosely from the base of the body adapted to have the feet contact with said laminated base and to simulate dancing when 80 the toy is agitated. 85

In testimony whereof I affix my signature.
BURTON P. MERWIN.
